UNITED STATES PATENT OFFICE.

ADOLPH KREMER, OF NEW YORK, N. Y.

SCREW-DRIVER.

1,230,173.

Specification of Letters Patent. Patented June 19, 1917.

Application filed January 13, 1915. Serial No. 1,981.

To all whom it may concern:

Be it known that I, ADOLPH KREMER, a citizen of the United States, a resident of the city of New York, borough of Manhattan, in 5 the county and State of New York, have invented a new and Improved Screw-Driver, of which the following is a full and exact description.

In turning a screw driver, it is difficult to 10 keep its axis in line with that of the screw to which it is applied. Consequently its chisel-end is liable to escape from the notch of the screw.

My invention relates to the construction 15 of a screw driver by which these difficulties are corrected.

For this purpose I make the blade of a screw driver so it will move within a slot of the shank, which motion, with the rocking 20 motion of the chisel-end in the notch of the screw, acts, as it were, on a spherical joint.

Another feature of my screw driver is that it can be operated in a limited angle to the axis of a screw.

25 Another feature of my invention is the construction of a screw driver whereby blades with chisel-ends of different width, thickness and shape as well as broken blades, can be quickly attached and detached.

30 A further feature of my invention is its detachability for use on automatic screw drivers.

Additional objects of my invention will appear in the following complete specifications in which its preferences will be described.

In the drawings similar characters of reference indicate corresponding parts in all views in which—

40 Figure 1 is a vertical section showing one form of my improved screw driver;

Fig. 2 is a similar view of a modification;

Fig. 3 is a vertical section of the modification shown in Fig. 2 at right angles to 45 Fig. 2;

Figs. 4, 5 and 6 are elevational views showing the blades of Figs. 1, 2 and 3 respectively.

Figs. 7 and 8 are vertical sectional views 50 at right angles to each other of a third modification of my improved screw driver;

Figs. 9 and 10 are detailed views of the modifications shown in Figs. 7 and 2 respectively;

55 Figs. 11 and 12 are vertical sectional views

at right angles to each other of a fourth modified form of screw driver.

Referring to the drawings and particularly Fig. 1 *a* indicates the shank of the screw driver consisting of the usual round 60 metal rod with the lower end of the shank enlarged somewhat into generally rectangular cross section.

The blade *b* of the screw driver which is shown detached in Fig. 4 projects at its upper end into a slot in the lower end of the shank and is pivotally supported at the lower end of the shank by means of trunnions *k* working in bearings *l* in the shank of the screw driver on each side of the slot. The 65 bearings *l* and trunnions *k* are somewhat more than half a circle in extent so that when the blade of the screw driver is positioned to form an axial extension of the shank it will be held in its bearings. When, however, the 70 blade is turned to a sufficient angle to the shank it may be detached as will be obvious from an inspection of Fig. 10. To hold the blade against accidental detachment and also to prevent too free oscillation when the 75 screw driver is in use, the upper edge of the blade is provided with a notch over the center of the trunnions into which projects the end of the pin *c* mounted in a central bore 80 in the shank of the screw driver and pressed against the blade by a spring *d*. The edges of the notch are curved as shown to provide a surface which will force the pin back against the tension of the spring when the 85 screw driver blade is turned in its bearings. 90

The construction so far described is common to the modifications shown in Figs. 1 to 10 inclusive. In the construction shown in Figs. 1 and 4 the pressure spring is relied upon to prevent the withdrawal of the blade. 95 In the form shown in Figs. 2, 3, 5, and 6 I provide an additional construction to positively lock the blade against turning beyond a certain angle. For this purpose the edges of the notch in the top of the blade near the top of the convex projections on each side of the notch are provided with shoulders *m* adapted to engage the side of the pin *c* to hold the blade against pivotal movement sufficient to be withdrawn from its bearings. 100 In order however that the blade may be detached for renewal or substitution of a different size blade, I provide on one side a small bore *n* leading from the outer edge of the blade to a point in the wall of a notch 105 110

in advance of the shoulder *m* whereby a suitable pin, such as shown at *h*, Fig. 2, may be thrust into a bore to press against the end of the pin *c* and elevate the pin *c* to clear 5 the shoulder and to permit detachment of the blade.

The pin *h* may be provided as shown in the drawing with a screw threaded head whereby it may be set in a socket in the head 10 of the screw driver handle.

In the modification shown in Figs. 7, 8 and 9 the blade is locked against excessive motion by means of a pin *e* mounted in a cross bore in the shank of the screw driver 15 intersecting the top of the slot in which the upper edge of the blade turns. A spring *f* holds the pin slightly projected on one side and in such a position that a portion of its lower convex face lies in the path of the 20 projections on each side of the notch in the upper edge of the screw driver blade. The pin *e* is prevented from turning by the pin *c* which projects through a slot in the pin *e* for permitting its transverse movement. 25 The pin *e* is also provided with a notch in its lower edge which is brought into registration with the blade when the pin is pressed inward against the tension of its spring. In the construction shown in Figs. 11 and 12 30 the blade *b* is provided with a circumferential enlargement operating in a suitable socket in the end of the shank *a* and is held against excessive oscillation by means of a cross pin *g* projecting through the shank 35 and through the slot in the upper edge of the blade.

The method of using my improved screw driver and its advantages will be apparent from the construction shown in the drawings 40 as the blade is virtually held in its central position with sufficient pressure to resist the accidental side movement which happens if the blade were freely pivoted and causes it to give way under the pressure 45 against the screw. The movement permitted is quite sufficient to accommodate any angle between the axis of the screw driver and the screw and to prevent mutilation of the screw head. All the driving 50 pressure comes on the trunnions which may be as large as necessary to sustain the thrust and torsion of driving the screw.

Having described my invention, I claim 55 as new and desire to secure by Letters Patent:

1. In a screw driver, a shank, a blade pivotally attached to the end of said shank and detachable from said shank upon pivotal movement beyond a predetermined 60 extent, a yielding member carried by said shank and engaging said blade to yieldingly hold it in alinement with said shank but permitting a pivotal movement of the blade to an extent somewhat less than necessary 65 to detach said blade from said shank, said

blade and said member having coöperating parts shaped to engage and resist movement of the blade beyond said permitted movement.

2. In a screw driver, a shank, a screw driver blade in the end of said shank and detachable therefrom upon pivotal movement beyond a predetermined extent, means for releasably and positively limiting the angular movement of said blade to less than 75 such predetermined extent, and for normally holding said blade yieldingly in alinement with said shank.

3. In a screw driver having a slotted shank, a blade mounted for pivotal movement in the end of said shank, and having an extension working in said slot and means for engaging said extension to yieldingly hold said blade in alinement with said shank and to positively limit the extent of 85 pivotal movement of said blade.

4. In a screw driver having a slotted shank, a blade pivoted in the end of said screw driver, said blade having an extension lying in said slot, a yielding member 90 mounted in said shank and engaging said extension to yieldingly hold the blade against angular movement, said yielding member and extension having coöperating parts arranged to engage after a predetermined pivotal movement of the blade away 95 from its position of alinement and resist further movement.

5. In a screw driver, a shank, a blade pivotally mounted in the end of said shank, 100 the pivots and bearings of the blade and shank respectively being shaped to permit detachment of the blade when turned beyond a predetermined distance from a position of the shank, and means for yieldingly 105 holding said blade against angular movement from said position, said blade and said means having coöperative parts arranged to engage after a predetermined movement of the blade from its position of alinement less 110 than the movement necessary to detach the blade and resist further movement of the blade.

6. In a screw driver, a shank, a blade pivotally mounted in the end of said shank, 115 the pivots and bearings of the blade and shank respectively being shaped to permit detachment of the blade when turned beyond a predetermined distance from the normal position with the edge of the blade 120 at right angles to the axis of the shank, a locking device for preventing movement of the blade beyond such predetermined angle, said locking means permitting angular movement within such angle while in locking 125 position.

7. In a screw driver, a shank having a slotted end, a blade in said slot, trunnions projecting from the opposite faces of said blade, the ends of said slotted shank being 130

- provided with bearings for said trunnions, said bearings being open on the lower edge through an angular distance less than 180° and said trunnions being cut away on their lower face to present a transverse dimension of less extent than the open lower edge of the shank bearings, while retaining a full 180° pressure receiving surface upon the upper half of the trunnion.
- 10 8. In a screw driver, a shank having a slotted end, a blade in said slot, trunnions projecting from the opposite faces of said blade, the ends of said slotted shank being provided with bearings for said trunnions, said bearings being open on the lower edge through an angular distance less than 180° and said trunnions being cut away on their lower face whereby the blade may be released from the shank when angularly
- 15 turned beyond a predetermined extent, and locking means permitting while in locking position angular movement of the blade

within such extent, but preventing movement beyond such angular extent until positively released.

25

9. In a screw driver, a shank having a slotted end, a blade pivotally mounted in said slot, the upper edge of said blade being shaped to present a central depression with cam faces rising on each side of said depression, a spring-pressed pin engaging the edge of said blade to hold the same yieldingly in alinement with the axis of the shank, and stops formed on said blade at the outer edges of said cam faces for positively preventing rotation of the blade beyond a predetermined extent.

30

In testimony whereof, I have signed my name to this application in the presence of two subscribing witnesses.
